UNITED STATES PATENT OFFICE.

NATHAN T. MELVIN, OF LODI, OHIO.

BEDSTEAD.

SPECIFICATION forming part of Letters Patent No. 252,490, dated January 17, 1882.

Application filed November 25, 1881. (No model.)

To all whom it may concern:

Be it known that I, NATHAN T. MELVIN, of Lodi, in the county of Medina and State of Ohio, have invented a certain new and Improved Bedstead; and I do hereby declare that the following is a full, clear, and complete description thereof.

My improvement relates to bedsteads, the nature of which consists in the peculiar construction and arrangement of the parts for uniting and connecting the sides and ends together, by which the head and foot are readily attached to and separated from the side pieces or rails, the principal object being to render the article cheap, durable, and light, that it may be used with facility as a portable bedstead as well as stationary.

For a full understanding of the invention and a further and more complete description thereof, reference will be had to the following specification, and to the annexed drawings, making part of the same, in which—

Figure 1 is a perspective view of one form of constructing the bedstead. Fig. 2 is a view of the corner sections. Fig. 3 is a top view of the corner sections. Fig. 4 is a detached section, which will be referred to in description.

Like letters of reference refer to like parts in the several views.

The bedstead herein represented is made entirely of round pieces, (turned in a lathe,) which are preferable for cheapness and lightness and sufficiently strong for all the purposes designed. The improvement is, however, applicable to other forms and constructions without departing from the nature of my invention.

In the drawings, A represents the posts; B, the head-section; C, the foot-section, and D D' the side sections, as seen in Fig. 1. The said head, foot, and sides are in separate sections, each of which are connected together by being attached to the corner-posts A by means of the clamps or lugs a a' and b b', Figs. 1 and 2, there being two clamps in each post for the side rails or sections, and also two clamps at right angles thereto, or nearly so, in the posts for the attachment of the head and foot sections. These lugs are alike and connected with the posts all in the same way. Hence it will not be necessary to describe each one separately.

Each lug is secured to the post by means of two or more pins or dowels, c, the ends of which

are secured respectively in the lugs and posts in such way as to admit of the space between the posts and lugs, as seen in Fig. 2, being wider 55 above the pins than below, which causes the said space to be tapering, whereby the bars E F of the end and side sections are clamped or wedged in between the lugs and posts, as seen in Figs. 2 and 3.

Near the ends of the bars E F is cut a groove, one on each end, as indicated at d d, Fig. 4. This groove is the segment of the post's circumference on one side and that of the lugs on the other, so that the several sections of the 65 bedstead are together as seen in Fig. 1. A jointed connection of the posts with the bars is firmly secured in the manner seen at A a b, Fig. 3. The grooves in the ends of the bars fit in between the lugs and posts, as indicated at d 70 d, Fig. 3. The said grooves in the bars prevent the side and end sections from slipping or moving out from between the posts and lugs, either in a lateral or transverse direction, and the only way to remove the section or take the 75 bedstead apart is by raising up the side and end sections, that the bars may be free from between the lugs and posts.

The bedstead is set up by entering the lower bar at the groove d between the lower lug and the post, and at the same time entering the upper one in the same way between the upper lug and the post and by forcing down the sections. When in this position the bars become tightly clamped between the lugs and posts, 85 and the greater the force exerted in bearing down the sections the more tightly and securely the joints are held, as the space between the posts and lugs is tapering by the angular or oblique position of the lugs in relation to the 90 posts. Hence the weight of the spring-bottom, which may be connected with the lower bars of the sections, as seen in an application pending for said spring-bottom, and the weight constantly more or less exerted in the use of 95 the bedstead, will constantly tend to tighten the bars to the post in the manner described.

The bedstead can be readily taken apart and the sections compactly laid one upon the other for transportation, as the article is light and 100 easily handled.

What I claim as my invention, and desire to secure by Letters Patent, is—

1. In bedsteads, the posts thereof having

lugs connected therewith in an angular or oblique relation to said parts, in combination with the bars or rails of the side and end sections, substantially as described, and for the purpose set forth.

2. In bedsteads, the rails or bars of the sides and sections of the ends, provided with grooves *d*, in combination with the lugs connected with the posts, arranged to clamp the said bars between the lugs and posts, substantially as described.
3. A bedstead constructed entirely of rounded

turned posts and made up in sections, consisting of the sides, ends, and posts connected together by clamping the sides and ends between the lugs and posts, substantially as described, and for the purpose specified.

In testimony whereof I affix my signature in presence of two witnesses.

NATHAN T. MELVIN.
